(57) **CLAIM**

The ornamental design for an electrical toaster, as shown and described.

DESCRIPTION

FIG. 1 is a front right side perspective view of an electrical toaster showing my new design;

FIG. 2 is a front left side perspective view thereof;

FIG. 3 is a front right side perspective view thereof; shown with the bread holder partially removed for completeness of illustration;

FIG. 4 is a top plan view thereof drawn on a reduced scale;

FIG. 5 is a bottom plan view thereof drawn on a reduced scale;

FIG. 6 is a perspective view of bread holder; shown with the support end being transparent and shown separately for ease of illustration; and,

FIG. 7 is a perspective view of bread holder; shown with the support end translucent/solid and shown separately for ease of illustration.

The broken lines in FIG. 6 and 7 are for illustrative purposes only and form no part of the claimed design.
